UNITED STATES PATENT OFFICE.

JOSEPH BOZIC, OF JOHNSTOWN, PENNSYLVANIA.

REGISTER.

1,187,808.

Specification of Letters Patent. Patented June 20, 1916.

Application filed July 7, 1915. Serial No. 38,501.

To all whom it may concern:

Be it known that I, JOSEPH BOZIC, a citizen of the United States, residing at Johnstown, in the county of Cambria and State of Pennsylvania, have invented certain new and useful Improvements in Registers, of which the following is a specification, reference being had to the accompanying drawings.

10 This invention relates to certain improvements in registers and has relation more particularly to a device of this general character especially designed and adapted for use in connection with coin receptacles used 15 in connection with pay-as-you-enter cars; and an object of the invention is to provide a register including novel and improved means whereby the same is operated under the influence of a coin whereby an accurate 20 record may be kept relative to the aggregate of the coins.

The invention consists in the details of construction and in the combination and arrangement of the several parts of my improved register whereby certain important 25 advantages are attained and the device is rendered simpler, less expensive and otherwise more convenient and advantageous for use, all as will be hereinafter more fully set 30 forth.

The novel features of the invention will be carefully defined in the appended claim.

In order that my invention may be the better understood, I will now proceed to describe the same with reference to the accompanying drawings, wherein—

Figure 1 is a view, partly in elevation and partly in section, illustrating a register constructed in accordance with an embodiment 40 of my invention; Fig. 2 is a sectional view taken substantially on the line 2—2 of Fig. 1; and Fig. 3 is a fragmentary view, partly in elevation and partly in section, illustrating a register constructed in accordance with 45 a further embodiment of my invention.

As disclosed in the accompanying drawings, A denotes a portion of a coin receptacle and C denotes a chute or conduit through which the coin or check passes, said chute 50 being so disposed as to permit the coin to pass therethrough by gravity. As the construction of the receptacle A forms no part of my invention, it is not thought that a detailed description or illustration thereof 55 is necessary. Suitably supported within the

receptacle A is a register mechanism R preferably of a structure similar to that disclosed in my Patent No. 1,141,309, issued June 1st, 1915, and including the lever 1 terminating in close proximity to the chute 60 or conduit C and pivotally supported intermediate its length above the lever 1 is the arm 2, the opposite extremities of which being provided with the rotatably supported disks 3, the lower disk being adapted for 65 contact with the upper face of the lever 1 while the upper disk is normally projected within the conduit or chute C under the influence of the spring 4, said conduit being provided in its adjacent side wall with an 70 opening 5 to permit the entry within the chute or conduit C of the upper roller 3 and the adjacent extremity of the arm 2, said spring also serving to maintain the lever 1 normally in operative position relative to 75 the transfer mechanism T of the register R. As herein embodied, the spring 4 is coiled and has one extremity suitably secured to the pivot a of the arm 2 and its opposite extremity to the lever 1 whereby the retractable 80 influence of the spring serves to maintain the lever 1 and the arm 2 in operative adjustments. As the coin or check passes through the chute or conduit C, the upper end portion of the arm 2 is forced outwardly 85 with a corresponding depression of the lever 1 with a resultant operation of the register R or more particularly the transfer mechanism T thereof, as it is to be observed that the upper roller 3 extends sufficiently within 90 the chute or conduit C as to obstruct the path of travel of the coin or check. It is to be also observed that the upper roller 3 extends within the chute C a distance less than the space between the pivot a and the 95 adjacent wall of the chute C so that the lever 2 will not be disposed past a vertical center when the upper roller 3 is forced outwardly under the influence of a coin or check.

In Fig. 3 I have illustrated a slightly modified form of my improved device which is substantially identical to the form hereinbefore set forth, except that the upper extremity of the arm 2a has operatively engaged therewith the endwise movable member 6 which partially intersects the chute or conduit C' and has its free extremity provided with the disk 7. As herein embodied, the upper extremity of the arm 2a is pro- 105 110

vided with a lateral extension 8 insertible within the slot 9 produced in the upper extremity of said arm 2^a.

From the foregoing description, it is thought to be obvious that a register constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the scope of the appended claims and for this reason I do not wish to be understood as limiting myself to the precise arrangement and formation of the several parts herein shown in carrying out my invention in practice.

20 I claim:

In combination with a chute, a register including an operating lever mounted for swinging movement, an arm mounted for rocking movement above the lever, said arm

being pivotally supported intermediate its 2^b length and having one extremity slidably engaged with the operating lever and its opposite extremity partially intersecting the chute immediately adjacent the entrance end of the chute, and a retractile spring interposed between the rock arm at its pivotal point and the operating lever of the register in advance of the contact between the rock arm and the lever for normally maintaining the rock arm partially intersecting the chute 35 and for maintaining the operating lever normally in operative position, said arm being of a length greater than the distance between the parallel planes occupied by the point of intersection between the arm and 40 chute and occupied by the operating lever when in its normal position.

In testimony whereof I hereunto affix my signature in the presence of two witnesses.

JOSEPH BOZIC.

Witnesses:

WALTER E. GLASS,
C. W. MOSHOLDER.
